ATTACHING CLIP FOR METAL MOLDINGS

William R. Wiley, Detroit, Mich.

Application November 1, 1935, Serial No. 47,878

8 Claims.

(Cl. 85—5)

This invention relates to clips for attaching metal molding strips to plain sheet or panel surfaces such as the metallic body, hood or similar portion of a motor vehicle, and has for its object an improved deformable piece, preferably stamped from sheet metal, which when positioned in the manner to be described relatively to the two parts whose union is to be effected, effects a permanent anchorage of the molding strip upon the panel piece. The construction offered is not only capable of cheap and rapid fabrication in quantities, but also lends itself to rapid installation in its intended position, and to permanent tenure of the parts in their desired relation.

In the drawing:
Figure 1 is a plan view from beneath, that is from the under side of the supporting panel and looking at the under side of the molding piece, of one of my clip pieces in position with respect thereto, its initial position being indicated in full lines and its other or clinching position in dotted lines.

Figure 2 is an end sectional elevation taken along the line 2—2 of Figure 1 and looking in the direction of the arrows there shown.

Figure 3 is a side elevation partly broken away taken along the line 3—3 of Figure 2, and looking in the direction of the arrows there shown, showing the clip in its deformed or finally clinching position.

Figure 4 is a plan view from above of one of the clips disassociated from other parts.

Figure 5 is a side elevational view of one of the clips similarly disassociated from the other parts.

Figure 6 is a view of the clip, panel and molding piece taken from the same position as Figure 1, showing the method of initially inserting the clip through the apertured panel and between the webs of the molding, and of its clinching position which results from a ninety degree turning of its body about one end as a center from its inserting position.

Figure 7 is a side elevational view similar to Figure 3, but showing the clip in its turned position just described as Figure 6, but before it has been deformed into the contour shown in Figure 3.

Figure 8 is a fragmentary plan view of a panel sheet, showing the possibility of employing a pair of suitably spaced holes instead of a single slot for the locking engagement of the end portions of the clip.

A indicates a panel of sheet metal such as is

used for the hoods or radiator shells of motor vehicles, and B indicates a frequently used form of molding provided with inturned flanges C. The web of the panel A is pierced at spaced selected positions with slots D.

The clips E consist of stampings of sheet metal, suitably bent for effecting their initial positioning relatively to the supporting panel and molding strip. What may be described as the right hand end of the clip as viewed in the several figures consists of a tongue E' provided with lateral ears or projections E²; next to it toward the left is a preferably slightly curved or dished portion E³ which leads to the shouldered portion E⁴ which is broader than the dished portion E³, indeed of about the same breadth as the spread of the tongues or ears E'. At the left hand edge of this broader part E³ the clip is sharply bent to practically right-angular form, as well as narrowed once more as at E⁵, and next adjacent this narrowed portion is another broadened or cruciform portion E⁶, beyond which at the left hand of the clip is an again narrowed tongue portion E⁷.

The clip as thus contoured and finished in quantity is positioned through the slot D and the space between the molding flange edges C in a position perpendicular to the lengthwise extent of the latter, so that the head portion with its projecting ears E' lies within the molding-enclosed space in the position shown at a in Figure 6. It is then swung to the left through a 90° angle until it attains the position shown in Figure 6 as position b. Because of the sharply angular shape of the clip as finished, the tongue E⁷ then lies within one end of the slot D when the head portion E' is still rather loosely adjacent the other or right hand end of the slot D, but, as brought out in Figure 7, the angled center portion of the clip is, in this position, appreciably above the plane of the panel A. Either pressure or a mallet blow upon the elbowed or center portion of the clip when in this position then effects its deformation so that the tongue E⁷ is forced under the adjacent or left hand end of the slot D, while the opposite end E' of the clip has its laterally projecting ears similarly forced under the metal web A beyond the opposite end of the slot D. The degree to which either end can be projected under the metal webbing is, however, limited by the shoulders formed by the broader parts E⁴ and E⁶ respectively, on either side of angled central portion, since these, being of greater spread than the width of the slot D, ride along the adjacent under surface of the panel A, that is to say the surface opposite that whereon

the molding strip is positioned, in a way to accentuate the under turning of the end portions E' and E⁷ beneath the ends of the slot D and molding flanges C respectively to the degree illustrated in somewhat exaggerated form in Figure 3, wherein the tongue E⁷ is shown so distinctly projected beyond the left hand of the slot D that it can not thereafter escape therefrom, while the laterally projecting ears E' at the opposite end of the clip have similarly been forced into clinching engagement with the interior surfaces of the inturned flanges C on the molding piece B.

While not indispensable, it should be noted that the pronounced indentation or concaving of the part E² next adjacent the flange engaging ears E' imparts a strength to the web of the clip at that point such that in cooperation with the more or less pivoting action of the shoulders E⁴ against the molding flanges C the tendency of the right-hand tip of the clip piece adjacent the ears E² to very definitely clinch the molding strip flanges C is accentuated. If, however, the gauge and hardness of the constituent metal of the clip be suitably chosen, this reinforcement of the clip body at this point by the concavity E³ is not essential, the central feature of the invention being the retention of the central portion of the clip, that is the parts E⁴ on one side of the central angle and of the parts E⁵ and E⁶ on the other side of the central angle outside of the plane of the panel A, while the tip portions E' and E⁷ engage permanently underneath the ends of the slot B therein, the end portions E' reaching through to engagement with the edges of the flanges C on the molding, while the tip of the portion E⁷ is merely clinched under the opposite end of the slot D with its sides, as brought out in Figure 6, still spaced from contact with the marginal edges of the flanges C. The exact width of the tongue E⁷ is, however, immaterial, so long as it be less than the space between the meeting edges of these flanges.

It will of course be obvious that since the central portion of the clip comprising the parts E⁴, E⁵, and E⁶ are in the finished assembly at all times located outside of the plane of the supporting panel A, a pair of suitably spaced holes, for the engagement into one of them of the parts E', E², and E³ and into the other of the tongue E⁷, may be employed instead of the continuous slot D hereinabove described. In such case under some circumstances the provision of the shoulder projection E⁶ might be dispensed with, though in order to keep the tongue E² from reaching too far into its receiving aperture the retention of the shoulder E⁴ would seem advisable. It is not necessary that the holes be round, as shown at A' or slightly elliptical as shown at A², in Figure 8 so long as they be so aligned and spaced that the end E' and the shouldered part E² of the clip may find anchorage through one of the holes, while the tongue E⁷ similarly engages through the companion hole.

What I claim is:

1. A deformable clip for effecting the attachment of a molding strip to a supporting panel, comprising a unitary sheet metal piece bent to longitudinally angled contour, the tip portions of the clip being adapted to operatively engage the inner flanged surface portions of the molding strip and the inner surface of a selectively apertured supporting panel respectively, and intermediate shoulder portions on said clip on either side of its angularly bent middle portion

adapted to laterally engage the inner surface of the supporting panel to limit the degree of possible projection of the body of the clip through the apertures respectively entered by its terminal portions and to maintain said central portion of the clip's middle portion in slightly spaced, parallel relation to the plane of the supporting panel along the inner surface thereof when the clip is driven to clinching position by pressure effected flattening out of its angled middle portion.

2. A sheet metal clip for effecting the structural correlation of a molding strip and a supporting panel, the latter having selectively aligned apertures, consisting of a unitary sheet metal stamping initially of substantially right-angled contour, provided intermediate its end portions with spaced laterally projecting shoulders, and at one end with a lengthwise extending tongue and at its other end with laterally projecting ear portions, the tongue portion being adapted to be forced, by straightening pressure upon the angled center portion of the clip, into engagement under one end of a slot in the supporting panel, and the opposite end portion being similarly forced into engagement, with its laterally projecting ear portions, against the inner surfaces of the inturned flange portions of the molding strip, the degree of possible projection of the recited end portions of the clip through their respective panel apertures being limited by the engagement of said shoulder portions against the adjacent outer surface of the supporting panel surrounding said apertures.

3. A clip member for attaching a molding strip with inturned flanges to a supporting panel which is provided with a series of aligned apertures, comprising a deformable sheet metal stamping of initially angular contour from end to end, its contouring, when viewed in plan being successively from one end to the other, an end tongue portion, a laterally branching shoulder portion, a relatively attenuated intermediate portion, a second laterally branching shoulder portion, a slightly concaved attenuated portion, and a terminal portion with laterally branching ears, said last named portion and the first named tongue portion being adapted to be forced in opposite directions lengthwise of the molding strip and into clinching engagement with the inner surfaces of the flanged portion of the molding strip and with the inner surface of the panel as a result of pressure applied to the angled central portion of the clip which tends to move the several parts thereof toward positions of substantial alignment, and said shoulder portions serving, by their engagement against the adjacent surface of the apertured supporting panel, to limit the degree of possible projection of said first-named tongue portion and of said terminal portion through their respective panel apertures when a flattening force is applied to the initially angular central portion of the clip.

4. A sheet metal clip of initially angular contour from end to end, adapted to be positioned at its ends through apertures in a supporting panel, with one end which is provided with laterally extending ears extending also between the opposing edges of an inwardly flanged molding strip held in registering position along the apertured portion of the panel, parts of the intermediate portions of the clip's body on either side of its central angularly bent portion being provided with laterally projecting shoulders of greater spread than the width of the aperture

in the panel, whereby these portions are prevented from passing therethrough, said clip as a whole being adapted to be deformed by pressure upon its central angled portion to cause its described 5 terminal portions to interlockingly engage their described adjacent molding strip flange and panel portions respectively.

5. A sheet metal clip adapted for the structural integration of an alignedly apertured panel 10 member and of a molding strip having inturned flanges, consisting of an angularly bent stamping having a projecting tongue portion at one end and a pair of laterally projecting ears at its other end, a pair of laterally projecting shoulder 15 portions, one located on each side of the angularly bent and relatively attenuated center portion of the clip, the body of the clip being adapted to be deformed by pressure applied to its angular central portion almost into plane alignment of 20 its several parts, thereby forcing its terminal tongue portion into engagement under the panel metal at one end of the slot therein, and forcing its opposite end with the laterally projecting ears into holding engagement with the interior 25 surfaces of the flanged portions of the molding strip adjacent their opposing edges.

6. A sheet metal clip for effecting the attachment of a molding strip to a selectively apertured supporting panel, comprising an initially angularly bent stamping having one terminal portion adapted to engage through an aperture in the supporting plate and against the remote surface thereof, and its other end having a shouldered terminal portion adapted to engage through the 30 supporting panel and over the edges of the in-turned flange portion of the molding strip, the intermediate portion of the clip being provided with laterally broadened portions adapted to engage against the adjacent panel surfaces and to 35 thus hold the central web portion of the clip against the adjacent side of the supporting panel despite the intended clinching deformation of the clip by pressure applied to the angled intermediate portion thereof.

45 7. A formed clip of laminary material for effecting the positioning of a molding strip upon a supporting panel having spaced apertures corresponding in position to the desired location of the molding strip thereon, said clip comprising 50 an initially angularly bent stamping, one of whose ends is adapted to engage through one of the

holes in the supporting panel and to be bent to position of substantial parallelism with the plane of the latter by deforming pressure upon the initially angular central portion of the clip, said clip being provided with a plurality of pairs 5 of laterally extending arms, one pair being located on either side of the centrally bent portion and one pair being in position to limit the degree of possible projection of the panel-engaging end portion of the clip through its selected panel 10 aperture, the other pair of arms, located in the opposite end of the clip from that last referred to, being adapted to be passed through an adjacent aperture in the panel and moved to position of engagement with the interior edge surfaces 15 of the inturned flanges of the molding strip, and to be forced into clinching engagement therewith by the described deformation of the initially angular central portion of the clip, which deformation results in a modification of the 20 initially angular side elevational contour of the clip toward a position of such alignment with the plane of the supporting panel as the positioning of the several parts of the clip on opposite sides thereof makes possible.

8. A unitary stamping of initially angled side-elevational contour adjacent its center portion, provided with pairs of laterally projecting arms on either side of said angularly bent center portion, and a terminally located pair of arms adapted to be passed through a hole in a supporting panel and between the inturned flanges of a molding strip positioned against the opposite face of the panel from that to which the clip is applied, and the end of the clip opposite to that 30 whereon its pair of flange-engaging arms are located being adapted to be passed through an adjacent hole in the supporting panel, the clip being adapted to be bent to clinching position by deforming pressure on its angularly bent center portion which drives the terminally located arms into clinching engagement with the molding strip flanges, and which drives the other end of the strip into position approaching parallelism 35 with the plane of the supporting panel, the degree of its possible projection through its chosen aperture in the supporting panel being limited by the engagement of the second one of the pair of laterally projecting arms against the adjacent surface thereof bounding such panel aperture. 40 45 50 55
